UNITED STATES PATENT OFFICE.

JOHN H. GREER, OF SAN FRANCISCO, CALIFORNIA.

SAVINGS BANK.

1,417,164.

Specification of Letters Patent. Patented May 23, 1922.

Application filed January 12, 1921. Serial No. 436,674.

To all whom it may concern:

Be it known that I, JOHN H. GREER, a citizen of the United States, and a resident of the city and county of San Francisco, State of California, have invented a certain new and useful Savings Bank, of which the following is a specification.

This invention relates to savings banks and more particularly to the type consisting of small portable home banks for the reception of coins and paper money if desired and which banks are provided with locks and keys.

It is one of the objects of the present invention to provide a small home savings bank that is not only simple, practicable, substantial and durable, but is also of an ornate appearance and, further, may serve as an article of utility because of its peculiar shape.

A further object of the present invention is to provide a home savings bank of inexpensive type of construction so that the devices may be readily distributed by banking institutions and others interested as an advertising medium to encourage thrift and financial savings with a mutual beneficial result to the recipients of the banks for enabling the safe collection of money, and to the distributors of the banks in resultant business gain.

It is a further object of the invention to provide a bank that while inexpensive and simple is of such type of construction as to be comparatively secure against opening and against the removal of inserted coins or other money.

The invention possesses other objects and features of advantage, some of which, with the foregoing, will be made manifest in the following description of the preferred form of the invention which is illustrated in the drawings accompanying and forming part of the specification. It is to be understood that it is not intended to limit the invention to the embodiment shown by the said drawings and description as variations may be adopted within the scope of the invention as set forth in the claims.

50 Referring to the drawings:

Fig. 1 is a side elevation of the improved bank.

Fig. 2 is a plan view of one of the sections of the bank looking into the interior thereof.

Fig. 3 is a longitudinal section on the plane indicated by lines 3—3 Fig. 2.

Fig. 4 is a detail elevation of the interlocking connection between the sections and the snap lock device preventing relative rotation.

Fig. 5 is an inside elevation of the guard covering the coin slot of the shell of the bank, and

Fig. 6 is a cross section on line 6—6 of Fig. 5.

The invention may be embodied in various forms of construction but preferably is embodied in a shell of egg-shape which is made of separable sections adapted to interlock when telescoped and rotatively moved relative to each other; the shell being provided with a suitable form of snap or automatic lock to prevent relative rotation of the interlocked shell until a proper controlling key has been applied to release the lock. The invention further consists of a novel form of coin slot guard which, while permitting the ready insertion of objects, at the same time prevents an effectual barrier against the removal of the objects from the interior of the shell.

The attractiveness of the device is secured by the formation of the shell in the contour of an egg thus lending to the advertising feature of the device by the development of the idea that one should provide a so called "nest-egg" or savings for the future. Again this peculiar shape of the bank enables the utilization of the device as an implement in household for facilitating mending operation upon hose and half hose in lieu of the ordinary darning egg now commonly used.

Preferably the bank consists of a shell having sections 2 and 3 which while here shown as meeting on a plane transverse to the longitudinal axis of the egg-shaped body, yet may be constructed and formed so as to meet on any other plane taken across the shell. An object of separating the sections 2 and 3 on a line transverse to the axis of the egg-shaped body is to enable the shell sections to be readily telescoped at their meeting edges and then rotated to be interlocked against lateral separation.

Suitable interlocking means for securing the sections against lateral separation may be employed and the preferred form of such means is here shown as including a series 5 of pins 4 provided on one of the sections, in this case on section 2; these pins being arranged on the interior of the shell and at a slight distance inwardly from the circular edge 5 thereof. The complementary section 10 3 is provided with an inwardly rebated or flange-like portion 6 adapted to telescope in the circular mouth of the section 2 and is provided with a series of L-shaped bayonet slots 7 into which the locking pins 4 first 15 move as the sections have been moved telescopically. After the edge 5 of the section 2 closely approaches the contiguous edge 8 of the section 3 then the sections are relatively rotated until the pins 4 pass into the 20 heel 7^a of the bayonet slot which will therefore hold the sections against lateral separation until the pins are again turned into the mouth of the slot.

Means are provided for automatically 25 locking the sections in their assembled position after the securing pins have been passed into the heels of the slots; the locking means serving to prevent rotation of the sections upon each other until a suitable and con- 30 trolling key has been inserted into the lock to withdraw its bolt from a coordinate portion of one of the shell sections. To achieve simplification and economy in construction a locking device is employed which has a 35 bolt coordinate to one of the bayonet slots 7 so that one of these slots is utilized in combination with the locking device to hold the sections against rotation. To this end a simple and suitable form of cabinet lock 10 40 having a bolt 11 is provided on the interior, in this case of the section 2 and so disposed that its bolt 11 automatically projects along the contiguous side of the section and adjacent the edge 5.

The lock 10 is so disposed with respect 45 to one of the bayonet pins 4 that when the section 2 is assembled upon the section 3 the several pins 4 will take a position at the mouth of the slot 7 at which time the bolt 10 50 11 of the lock will bear upon the edge 6^a of the portion 6 and the bolt will be repressed as the sections 2 and 3 are telescoped and as the pins 4 move into the slots 7. When the circular edges 5 and 8, Fig. 3, 55 come into abutment then the sections are relatively rotated so as to carry the pins 4 into the heels 7^a of the bayonet slots at which time the bolt 11 will ride from the edge 6^a into the mouth of the contiguous 60 slot 7 as clearly shown in Fig. 4, whereupon the sections will be locked against relative rotation until a suitable key K shown in dotted lines in Fig. 3 is inserted into the lock and the bolt retracted.

One of the shell sections is provided with 65

a coin slot 12, Fig. 6, for the reception of coins which are prevented from being extracted from the bank by suitable guard arranged upon the interior of the bank section. Such guard is here shown as comprising 70 series of oppositely disposed resilient tongues 13 yieldable upon the insertion of a coin or other object and closing together again after the full insertion of the coin or object in such manner as to prevent the retraction thereof. The several prongs 13 may be struck up from a frame portion 14 arranged about the coin slot 12 and suitably secured upon the interior surface of the bank section. A backing device may be utilized 75 to prevent undue separation of the guard prongs or tongues 13 and such device may comprise a box-like portion 15 having a mouth 16 at its inner base through which the tongues 13 project. The front portion 80 of the box 15 may bear upon the frame parts 14 and the whole guard structure may be readily and securely held in place by means of horns 17 struck inwardly from the ends 85 of the slot 12 and crimped over the end 90 walls of the box 15.

What is claimed is:

1. A savings bank consisting of a shell having separable sections with bayonet lug and slot interlocking means at their meeting 95 edges, and a snap lock whose bolt enters one of the slots for securing the sections assembled.

2. A savings bank consisting of a shell having separable sections with telescopic 100 meeting edges and bayonet interlocking means and an automatic snap lock for securing the sections after they have been rotated on each other to interlock.

3. A savings bank consisting of a shell 105 having sections with telescopic edges one of which edges is notched, a snap fastener projective into said notch for locking the sections in closed position, and means for interlocking the sections upon relative rotative movement in one direction.

4. A savings bank consisting of a shell having sections with telescopic edges, a snap fastener for locking the sections in closed 115 position, and means for interlocking the sections upon relative rotative movement in one direction the snap fastener being co-operable with a part of the interlocking means.

5. A savings bank consisting of a shell 120 having sections with pin and slot interlocking means, and a snap fastener co-operable with a slot of said interlocking means to lock the assembled sections against rotation.

6. A savings bank consisting of a shell 125 having sections with pin and slot interlocking means, and a snap fastener co-operable with said interlocking means to lock the assembled sections, the bolt of the fastener projecting into a coordinate slot of the inter- 130

locking means as the sections are interlocked.

7. A savings bank consisting of a shell having sections telescopic and rotative to interlock and to disconnect, a fastener on one section with a spring bolt, the other section having an angular slot, the bolt being repressed as the sections are telescoped and automatically projecting into the slot as the sections are relatively rotated.
- 10 8. A savings bank consisting of a shell having sections telescopic and rotative to interlock and to disconnect, a snap fastener on one section with a spring bolt, the other section having an angular slot, the bolt being repressed as the sections are telescoped and automatically projecting into the slot as the sections are relatively rotated, and a pin interlockable in the slot to prevent extraction of one section from the other.
- 15 9. A savings bank consisting of a shell having sections telescopic and rotative to interlock and to disconnect, a snap fastener on one section with a spring bolt, the other section having an angular slot, the bolt being repressed as the sections are telescoped
- 20
- 25

and automatically projecting into the slot as the sections are relatively rotated, the bolt locking the sections against rotation.

10. A savings bank consisting of a shell having sections telescopic and rotative to interlock and to disconnect, a snap fastener on one section with a spring bolt, the other section having an angular slot, the bolt being repressed as the sections are telescoped and automatically projecting into the slot as the sections are relatively rotated, and a pin interlockable in the slot to prevent extraction of one section from the other, the bolt locking the sections against rotation.

11. In a coin savings bank, a shell having a coin slot, and a slot guard comprising a frame secured about the slot and having series of opposed, resilient tongues separable by an inwardly thrust coin, and a backing device for the tongues, the shell having horns struck in at the ends of the slot and clinched over the guard to secure it in place.

In testimony whereof, I have hereunto set my hand.

JOHN H. GREER.
